PHOTOGRAPHIC SENSITIVE MATERIAL

Alfred Miller, Dessau, Germany, assignor, by
mesne assignments, to General Aniline & Film
Corporation, New York, N. Y., a corporation of
Delaware

Application July 26, 1938, Serial No. 221,355
In Germany July 28, 1937.

7 Claims. (Cl. 95—2)

My present invention relates to photographic sensitive material.

In photographic multi-layer material in which the single layers are sensitized for different ranges of wave length there have been used anti-halation layers which are usual in panchromatic material. In selecting the anti-halation dyestuffs one starts from the standpoint that all the layers of the multi-layer material are affected disadvantageously by the excess radiation, so that it appears unconditionally necessary to protect all the layers of the film from the injuriously scattered rays.

It is an object of my invention to provide a photographic material having several differently sensitized layers, such as is used, for example, as a multi-layer material for color photography, wherein a sufficient protection is provided from the excess radiation by coloring the anti-halation layer with the color complementary to the color sensitivity of the layer adjacent to the support. If the lowest layer is sensitive to red, for example, the anti-halation layer is colored green. The anti-halation layer may be between the support and the lowest light-sensitive layer or on the rear face of the film. It is also possible to color the support itself.

Further objects of the invention will appear from the description following hereinafter.

It constitutes a considerable advance in the art to use, instead of an anti-halation layer, which acts as an absorbent for all the layers of the multi-layer material and, therefor, for all three fundamental regions of the spectrum, only one such layer, which needs be effective only for one component layer and indeed that which is adjacent to the support. Such an anti-halation layer obviously needs only one dyestuff, a yellow if the lowest layer is not especially sensitized, a red if it is ortho-chromatically or a green, if it is panchromatically sensitized. Moreover, there is a simplification and a greater certainty in the manufacture of the material, since it is advantageous in respect of durability of the emulsion which one has to regard in the selection of a suitable dyestuff that only a small quantity of an individual substance comes into question and, on the other hand, it is of advantage for the binding agent in which this dyestuff is embedded that the amount to be incorporated is only very small.

The choice of dyestuff must depend on the method of processing to which the material is later to be subjected, and there may be used those which are soluble or destroyed and, there-

fore, decolorized or removed either in reducing baths or in oxidizing baths.

As the binding agent for the anti-halation layer gelatin, cellulose derivatives, artificial resins, natural resins or the like may be used. It is also possible to apply dyestuffs without binding agents to the support, if desired with subsequent application of a thin layer of wax. Also colored resins with or without additional dyestuff may be used in suitable cases.

The anti-halation layers may be used for materials in which the layers carry dyestuff components for color development or dyestuffs or dyestuff components for the silver dyestuff-bleaching-out or silver-anti-diazotate processes. Also multi-layer materials without additions necessary for the production of color may be used.

The following examples, taken with the accompanying self-explanatory figures of drawing, illustrate the invention:

Example 1.—For a photographic multi-layer material, as shown in Figure 1, of which the lowest layer is sensitive to red, there is used on the rear face of the support an anti-halation layer which is colored with Light Green SF Yellowish (see Schultz, Farbstofftabellen, 7th ed., vol. I, No. 765).

Example 2.—For a multi-layer material the lowest layer of which is sensitive to green there is used an anti-halation layer which is colored with acid fuchsin (see Schultz, Farbstofftabellen, 7th ed., vol. I, No. 800).

Example 3.—For a multi-layer material the lowest layer of which is sensitive to blue there is used an anti-halation layer which is colored with the dyestuff made by condensing quinaldine-dimethylsulfate with para-methoxybenzaldehyde (see German specification No. 579,078).

Example 4.—For a multi-layer material, as illustrated in Figure 2, the lowest layer of which is sensitive to blue there may be used between the support and the light-sensitive layer an anti-halation layer which is colored with the dyestuff made from quinaldine-dimethylsulfate and diphenyl-dialdehyde.

Example 5.—For a multi-layer material having several differently sensitized layers, the lowest of which is sensitive to green, there is used as a rear layer an anti-halation layer colored with fuchsonic tricarboxylic acid.

Example 6.—For a multi-layer material having differently sensitized layers, the lowest of which is sensitized to red, there is used an anti-halation layer which consists of polyglucoronic acid col-

ored with alkali blue and is coated with a colorless lacquer soluble in the developing solution.

What I claim is:

1. A photographic material comprising a single support, a layer sensitive to light of a particular spectral range and carried on one side of said support, and at least one additional layer sensitive to light of a different spectral range and superimposed directly on said first mentioned light-sensitive layer, said support being provided with an anti-halation dyestuff which absorbs only the light of the spectral range to which the first mentioned light-sensitive layer adjacent said support is sensitive.

2. A photographic material comprising a single support, a silver halide gelatin emulsion layer sensitive to light of a particular spectral range and carried on one side of said support, and at least one additional silver halide gelatin emulsion layer sensitive to light of a different spectral range and superimposed directly on said first mentioned light-sensitive layer, said support being provided with an anti-halation dyestuff which absorbs only the light of the spectral range to which the first mentioned light-sensitive layer adjacent said support is sensitive.

3. A photographic material comprising a single support, a silver halide gelatin emulsion layer sensitive to light of a particular spectral range and carried on one side of said support, and at least one additional silver halide gelatin emulsion layer sensitive to light of a different spectral range and superimposed directly on said first mentioned light-sensitive layer, said support having a rear layer containing an anti-halation dyestuff which absorbs only the light of the spectral range to which the first mentioned light-sensitive layer adjacent said support is sensitive.

4. A photographic material comprising a single support, a silver halide gelatin emulsion layer sensitive to light of a particular spectral range and carried on one side of said support, and at

least one additional silver halide gelatin emulsion layer sensitive to light of a different spectral range and superimposed directly on said first mentioned light-sensitive layer, and an intermediate layer between said support and the lowest emulsion layer, said intermediate layer containing an anti-halation dyestuff which absorbs only the light of the spectral range to which the first mentioned light-sensitive layer adjacent said support is sensitive.

5. A photographic material comprising a single support, a silver halide gelatin emulsion layer sensitive to red and carried on one side of said support, and at least one additional silver halide gelatin emulsion layer sensitive to light of a different spectral range and superimposed directly on said first mentioned light-sensitive layer, said support having a rear layer colored with Light Green SF Yellowish.

15 6. A photographic material comprising a single support, a silver halide gelatin emulsion layer sensitive to blue and carried on one side of said support, and at least one additional silver halide gelatin emulsion layer sensitive to light of a different spectral range and superimposed directly on said first mentioned light-sensitive layer, and an intermediate layer between said support and the blue-sensitized emulsion layer, said intermediate layer being colored with a dyestuff produced by condensing quinaldine-dimethylsulfate with diphenyldialdehyde.

20 7. A photographic material comprising a single support, a silver halide gelatin emulsion layer sensitive to green and carried on one side of said support, and at least one additional silver halide gelatin emulsion layer sensitive to light of a different spectral range and superimposed directly on said first mentioned light-sensitive layer, said support being provided with a rear layer colored with fuchsonic tricarboxylic acid.

ALFRED MILLER.
